UNITED STATES PATENT OFFICE.

FRANK PAVLIK, JR., OF WESTMINSTER, COLORADO.

DRY CLOSET.

1,265,368.

Specification of Letters Patent.

Patented May 7, 1918.

Application filed January 17, 1918. Serial No. 212,281.

To all whom it may concern:

Be it known that I, FRANK PAVLIK, Jr., a citizen of the United States, residing at Westminster, in the county of Adams and 5 State of Colorado, have invented certain new and useful Improvements in Dry Closets; and I do hereby declare the following to be a full, clear, and exact description of the invention, such as will enable others skilled 10 in the art to which it appertains to make and use the same.

This invention embodies improvements in dry closets of the indoor chemical type, and especially relates to that class, which are 15 readily attachable to and detachable from an air outlet conduit for ventilating purposes, which supplementally co-operates with the action of a suitable chemical or the like, preferably in liquid form, introduced 20 into the container for relieving its contents of foul odors and other unsanitary conditions.

The patented art, in this relation, having been sufficiently developed so that the general 25 aims and advantages of these types of closets are fully understood, it will be unnecessary to further initially refer to the objects of the present invention, which will be clearly apparent from the following description, though by way of emphasis it 30 may be said that the invention is more particularly adapted for use on the farm, home- stead, or other outlying localities, where the usual water flushing closets may not be feasible 35 bly installed, owing to lack of water facilities and sewerage systems.

With this general statement, the invention consists of the combination and structural arrangement of parts as hereinafter 40 closed, the essential features of novelty being more particularly set forth in the appended claims; but to more clearly understand the same, reference will now be had to the accompanying drawings, in which 45 like reference characters designate the same parts in the several views, of which—

Figure 1, is an elevational view of the installed closet, the upper portion thereof and the lower portion of the vent pipe being 50 shown partly broken away and in section; Fig. 2, is a top plan view, looking down toward the line 2—2 of Fig. 1, a section being taken through the lower end of the vent pipe; Fig. 3, is a fragmentary 55 view, showing the application of a pair of

eccentric binding clamps for the forward bottom of the apertured seat; Fig. 4, is a detail view of one of the split distending rings for the collapsible section of the vent conduit; Fig. 5, is a fragmentary cross-sectional view, taken on the line 5—5 of Fig. 4; and Fig. 6, is a detail front view of a wall plate for securing the upper elbow of the vent pipe to a chimney flue or the like.

10 designates the metallic lower section of the vent conduit, which lower section is in the nature of a hollow pipe, closed at its bottom, and rigidly secured to a side wall of the room, or other suitable support, as by means of the fastening nails 11. This 15 lower section of the vent conduit is positioned substantially above the floor, at a distance dependent upon the height of the container and its seat, hereinafter specifically referred to.

12 designates a metallic upper section of the vent pipe, which may be in the nature of an open ended hollow elbow, the lateral arm of which is adapted to snugly seat within a central aperture 13 of a wall plate 14, flatly secured to the wall of a chimney flue or the like by the nails 15, driven through diverging nail holes 16 in the wall plate 14, the angular divergence of which nail holes causes the nails 15 to be held securely against displacement by a wedging action. The aperture 13 of the wall plate, of course, registers with the usual opening in the wall of the chimney flue.

Between the lower and upper metallic 90 sections 10 and 12 is disposed an elongated tubular section 17, formed of an air tight, but freely flexible and collapsible cloth fabric or the like, such as canvas or duck, and the ends of which may be secured over the opposed open ends of the upper and lower metallic sections in any suitable way, shown in the drawings simply by wiring 18. This flexible intermediate tube is maintained open or distended by the spaced positioning of 95 resilient rings 19 interiorly of its length, which rings may be in the nature of annular bands, split or divided as at 20, to permit of their ready insertion within the fabric tube before installation, and which are 100 partly held in place by the outwardly punched pointed projections 21, with intermediate stitching 22, if desired.

The primary reason for making this intermediate section collapsible, is that it 110

avoids the necessity of connecting up a number of metallic sections, and enabling it to be knocked down and nested for packing the whole equipment in the container receptacle proper for shipment and storage, a matter of no mean importance in the saving of space and the avoidance of misplacing and oftentimes the loss of a part of the full equipment.

10 25 designates the closet proper or container, formed as a plain receptacle, preferably of galvanized sheet iron or the like, which may be easily enameled for cleanliness and neatness of appearance.

15 The lower peripheral wall of this container receptacle may be apertured to provide for the attachment of an outlet pipe 26, controlled by a valve 27, which outlet connection may be coupled up with a drain

20 pipe, through which the container may be emptied and flushed out as desired, although the simplicity of construction of the container enables it to be bodily removed for emptying, by means of the usual bail 28.

25 On the top of the container is detachably mounted an internal downwardly deflecting marginal rim 29, provided with the central enlarged opening 30, over which is mounted the seat 31, having the usual opening 32, and

30 which may be of two-part construction, hinged as indicated at 33, said apertured seat being in turn provided with a cover 34, hinged thereto as at 35.

The bottom face of the seat 31, which at 35 its rear extends substantially beyond the container 25, is recessed, as at 36, to span the rear wall of the container, providing a ventilating air passage around the rear top of the container, between the seat and the deflector rim 29.

37 designates the wall of an air casing, provided at its top with a marginal flange 38, secured in any suitable way, as by nails or screws, to the bottom of the seat 31, and 45 having a concave edge 39, struck on an arc conforming with the curvature of the container, so that this casing will snugly fit up against the rear wall of the container, immediately below the rear portion of the recess 36.

This arrangement provides for an enlarged ventilating chamber 40, communicating with the passage 36, and having its rear wall provided with an outlet aperture, encompassed by a flaring element 41. This latter receives and guides in place the conically tapered end of a hollow connecting pipe 45, having its other end cut away at the top, as at 47, and projecting into the lower 60 section 10 of the vent conduit through a circular opening 46. This end of the connecting pipe 45 is provided on opposite sides with slotted alining arcs 48, riding over a connecting pin 49, disposed transversely 65 within the section 10, thus coupling the con-

nection with the vent pipe with a limited pivotal swing, so that the tapered end of the connecting pipe may readily seat itself, by means of the guiding flaring element 41, into air-tight connection with the outlet aperture 70 of the chamber 40.

When so assembled, the closet seat may be more positively secured to the connecting pipe by means of a pivotal hook 43, engaging the pipe through a small aperture 44, 75 which will hold the tapered end of the connecting pipe firmly seated. The seat 31 itself is in turn clamped at its forward portion to the depending flange of the deflector rim 29, by means of the eccentrically mounted clamp elements 42 (see Figs. 2 and 3) thereby drawing the edge 39 of the casing 37 snugly against the wall of the container, making the whole attachment quite air tight.

If desired, the rear portion of the hinged 85 seat may be hooked at each side to the container base, to maintain the former in position, when the forward portion is unclamped and raised for urinal purposes. This has not been actually illustrated, as there is no 90 view which would properly show the connection, but it is so obvious that the showing is not believed to be essential, no claim being made thereto.

As in similar types of closets, I also employ a suitable chemical mixture in the container, and the noxious odors and gases, not entirely thrown down or killed by the chemical action, are carried away, as indicated by the arrows, through the vent pipe by way of 100 its coupling with the container. Also, while not essential, it is obvious that any of the well known means of forced draft, sometimes used in ventilating systems generally, might be employed, if desired.

105 With the foregoing complete disclosure, it is believed that a further detailed description of the operation would only be unnecessarily prolix, and while it will be understood that I do not make any broad claims 110 to the detachable coupling up of a dry closet container to a vent pipe generally, at the same time, I do not limit myself to the exact details as set forth, excepting as come within the terms of the ensuing, as viewed in the 115 light of the specification, contemplating a fair range of equivalents.

What I do claim as new and patentable, is:—

1. In dry closet fixtures, a container and seat therefor projecting substantially beyond the rear thereof, said seat being partly recessed, on its underneath face, to span the rear top edge of the container wall and provide a foul air passage thereover, in combination with a communicating ventilating chamber casing secured to said seat beneath said air passage, in detachable air tight contact with said container; a vent conduit; and a pipe coupling communicating between 120 125 130

said vent conduit and said ventilating chamber, in detachably connected relation to the latter, substantially as described.

2. In dry closet fixtures, a container and seat therefor projecting substantially beyond the rear thereof, said seat being recessed, on its underneath face, to span the rear top of the container wall and provide a foul air passage thereover, in combination with a communicating ventilating chamber casing secured to said seat beneath said air passage, in detachable air tight contact with said container; eccentrically mounted clamp elements disposed on the underneath forward face of said seat, for detachably securing said seat and ventilating casing to said container; a vent conduit; and a pipe coupling communicating between said vent conduit and said ventilating chamber, in detachably connected relation to the latter, substantially as described.

3. In dry closet fixtures, a container and a seat therefor projecting substantially beyond the rear thereof, said seat being partly recessed, on its underneath face, to span the rear top of the container wall and provide a foul air passage thereover, in combination with a communicating ventilating chamber casing secured to said seat beneath said air passage, in air tight contact with said container, said casing having a foul air outlet; a vent conduit having an inlet aperture in its periphery; a pipe coupling, projecting through said inlet aperture and opening into said vent conduit; pin and slot connections for pivotally retaining that end of the pipe coupling within said vent conduit; guiding means for directing the opposite end of said pipe coupling into detachably closed connection with said casing outlet; and means for fixedly holding said elements together when assembled, substantially as described.

4. In dry closet fixtures, a container and seat therefor projecting substantially beyond the rear thereof, said seat being partly recessed, on its underneath face, to span the rear top edge of the container wall and provide a foul air passage thereover, in combination with a communicating ventilating chamber casing secured to said seat beneath said air passage, in detachable air tight contact with the wall of said container; a vent conduit; a pipe coupling communicating between said vent conduit and said ventilating chamber, in detachably connected relation to the latter; and a valved outlet through the lower peripheral wall of said container, for emptying the contents of said container without detaching the latter, when desired, substantially as described.

5. In dry closet fixtures, a container, a

seat therefor projecting substantially beyond the rear thereof, and an intermediate apertured internal deflector rim, said seat being recessed, on its underneath face, to span the rear top of the container wall and deflector element, to provide a foul air passage thereover, in combination with a communicating ventilating chamber casing secured to said seat beneath said air passage; means co-operatively associated with said seat for holding said ventilating casing in air tight contact with said container wall; a vent conduit; a pipe coupling communicating between said vent conduit and said ventilating chamber, in detachably connected relation to the latter; and means for fixedly holding said coupling in place, when the elements of the fixture are assembled, substantially as described.

6. In dry closet fixtures, the combination of a seated container, vent conduit, and detachable connecting coupling elements therebetween, constructed and functioning substantially as disclosed, the said vent conduit comprising an upper and a lower fixed metallic section, with a collapsible fabric tubing intermediately connecting same, substantially as described.

7. In dry closet fixtures, the combination of a seated container, vent conduit, and detachable connecting coupling elements therebetween, constructed and functioning substantially as disclosed, the said vent conduit comprising an upper and a lower fixed metallic section, with a collapsible fabric tubing intermediately connecting same, and split rings disposed in spaced and secured relation within said fabric tubing, for normally holding same laterally distended when in use, but permitting of the nesting of same for storage and shipment, substantially as described.

8. In dry closet fixtures, the combination of a seated container, vent conduit, and detachable connecting coupling elements therebetween, constructed and functioning substantially as disclosed, the said vent conduit comprising an upper and a lower metallic section, with a collapsible fabric tubing intermediately connecting the same, and means for attaching the upper metallic section in register with the flue opening of a chimney, comprising a wall plate supporting said upper metallic section, and provided with a series of diverging nail holes, whereby when nails are driven therethrough into the wall they will hold said plate securely by a wedging action, substantially as described.

In testimony whereof, I affix my signature.

FRANK PAVLIK, JR.
